(57) **CLAIM**

The ornamental design for a bag for walker or wheelchair, substantially as shown and described.

DESCRIPTION

FIG. 1 is a front elevation view of a bag for walker or wheelchair showing my new design;

FIG. 2 is a front elevation view thereof;

FIG. 3 is a left side elevation view of the bag;

FIG. 4 is a front elevation view thereof;

FIG. 5 is a right side elevation view thereof;

FIG. 6 is a rear elevation view thereof;

FIG. 7 is a top plan view thereof;

FIG. 8 is a bottom plan view thereof;

FIG. 9 is a front elevation view thereof, with the attachment straps pulled out; and,

FIG. 10 is a rear elevation view thereof.

The broken line showing is included for the purpose of illustrating environment and forms no part of the claimed design.
